US00D679476S

(12) **United States Design Patent**
Barber et al.

(10) **Patent No.:** US D679,476 S
(45) **Date of Patent:** ** Apr. 9, 2013

(54) **SNACK FOOD PRODUCT**

(75) Inventors: **Keith Alan Barber**, Frisco, TX (US);
Deborah Fischer, McKinney, TX (US);
John Hildebrand, Flower Mound, TX
(US); **Enrique Michel**, Dallas, TX (US)

(73) Assignee: **Frito-Lay North America, Inc.**, Plano,
TX (US)

(**) Term: **14 Years**

(21) Appl. No.: **29/391,830**

(22) Filed: **May 13, 2011**

(51) **LOC (9) Cl.** 01-01

(52) **U.S. Cl.**

USPC **D1/125**

(58) **Field of Classification Search** D1/100-130,
D1/199; D7/359, 409, 388; 426/94, 144,
